TELEPHONE INSTRUMENT CIRCUIT

Emanuel Frydman, Liverpool, England, assignor, by mesne assignments, to Automatic Electric Laboratories, Inc., Chicago, Ill., a corporation of Delaware

Application September 3, 1942, Serial No. 457,119
In Great Britain September 6, 1941

5 Claims. (Cl. 179—81)

The present invention relates to telephone substation instrument circuits suitable for use in systems which follow the usual practice of employing low frequency alternating current for signalling a wanted party by the ringing of a bell or the like.

The invention finds particular application to two-party line circuits for use in automatic telephone systems in which the general arrangement is that the bells of the two parties sharing a line are earthed, one bell being connected to one leg of the line and the other bell to the other leg. In order to avoid the completion of direct current earth biasing circuits by way of the telephone bells, it is then desirable to connect a condenser in the earth circuit of each of the bells. With these arrangements, however, the changes in distributed exchange battery voltage at the substation end of a party line due to one of the parties setting up a call by dialling cause tinkling of the bells both to the calling party and of the other party sharing the line and it is possible for the tinkling of the second bell to be mistaken for ringing by the second party.

In telephone instrument circuits involving a single subscriber per line, the signalling bell is usually connected in series with a condenser across the line and arrangements are made to provide a low resistance shunt path for the bell during dialling, so as to prevent tinkling during this time. In this case, however, it is possible for bell tinkling to be produced by branches of trees making intermittent contact with open wire lines and also by maintenance men testing or working on the line. The invention has for its main object the provision of simple and efficient means for preventing the annoyance of bell tinkling due to the above mentioned and similar conditions.

According to the invention in a telephone system employing low frequency alternating current for signalling purposes, the circuit for the bell or the like in a substation instrument circuit includes a non-linear resistance element arranged to present a high resistance to the exchange battery voltage but to break down at the signalling current voltage.

The invention will be better understood from the following description of one method of carrying it into effect, reference being had to the accompanying drawing which shows circuits of the substation end of a two-party line assumed to extend to an automatic telephone exchange. The circuits of one of the party line stations A is

5 shown in full, while as regards the other station B, only the bell circuit of this has been shown, since the equipment thereat is identical with that of the first station, the only difference being that the line conductors are reversed so that the bell circuit connects with the opposite leg of the line.

Considering now the equipment at the first party line station A, this comprises the usual transmitter T, receiver R, three-winding anti-side tone induction coil comprising windings IC₁, IC₂ and IC₃, resistors YA and YB and switch-hook contacts SH₁ and SH₂ which close when the receiver or handset, as the case may be, is lifted. The subscriber's dial impulse contacts are designated IMP and other contacts of the dial (not shown) are closed when the dial is off-normal and serve in well-known manner to short-circuit the transmitter T and receiver R during dialling. 10 As regards the bell ringing circuit, this comprises the usual condenser 10 and bell 11, but in accordance with the invention the additional condenser through which the bell is normally connected to earth is now replaced by a non-linear resistance element 12. Similar 15 remarks apply in connection with the second party line station B with the difference that the bell 21 which is earthed via non-linear resistance element 22 is connected via condenser 20 to the opposite leg of the line compared with the bell 11. 20

In accordance with usual automatic exchange practice, alternating current at a voltage of the order of 75 volts is assumed to be used for ringing purposes, while as will be better appreciated later in the description, the voltages which ordinarily produce bell tinkling cannot exceed the voltage of the exchange battery which is normally in the neighbourhood of say 50 volts.

The function of the non-linear resistance devices 12 and 22 is essentially to discriminate between ringing and tinkling voltages so that on the one hand a low resistance will be offered to ringing currents and on the other hand a very high resistance will be presented to currents 45 which would tend to produce bell tinkling. For this purpose use could be made of neon tubes or like gas discharge devices which would be arranged to strike only at voltages greater than say 50 volts, but preferably the devices 12 and 50 22 take the form of small solid units of non-linear resistance material comprising a mixture of silicon carbide with carbon and/or tungsten or molybdenum which is agglomerated under pressure and subsequently baked. Such units can be arranged to present an extremely high

resistance at voltages up to say 55 volts, the resistance decreasing considerably with any increase of voltage above this value. This type of material can be conveniently made up in the form of discs about the size of a shilling, which can therefore be readily mounted inside the party line telephone instruments or in the telephone connecting blocks, thereby avoiding the mounting difficulties which are encountered when the instrument bells are connected to earth via condensers.

Considering now the telephone instrument circuit of party line subscriber A, the condenser 10 will normally be charged up to the exchange battery voltage of 50 volts in series with the line relay associated with the party line in question, but the bell does not tinkle when this circuit is first closed owing to the slow rate of charging of condenser 10 due to the high resistance of unit 12. When the subscriber initiates a call, the telephone instrument is looped across the line via the switchhook contacts SH2 and condenser 10 is discharged over contacts SH1, resistance YA, induction coil winding IC2, resistance YB, transmitter T, and dial impulsing contacts IMP. At the main exchange the loop thus completed operates the line relay and causes a first selector to be seized in well-known manner, whereupon battery is connected to the negative leg of the line via one winding of the selector impulsing relay and earth is connected to the positive leg of the line via the other winding of the relay.

When subscriber A dials the first digit of the required number, the dial impulse contacts IMP, in opening on the first break impulse, remove the shunt circuit from condenser 10 which now proceeds to charge up over the following circuit: battery at the main exchange, negative line, condenser 10, contacts SH1, resistance YA, induction coil winding IC2, resistance YB, induction coil winding IC1, contacts SH2, and positive line to earth at the main exchange. A charging path for the condenser is also completed via bell 11 and unit 12 to earth, but owing to the shunting effect of the previously mentioned comparatively low resistance earth circuit via contacts SH1, the voltage developed across unit 12 will be well below that required to produce breakdown thereof, and consequently it maintains its very high resistance which prevents tinkling of the bell. When the dial impulsing contacts reclose, the condenser 10 is again shunted down and on the next opening of the contacts IMP the cycle of operations already described is repeated but the bell 11 again fails to tinkle owing to the resistance of unit 12.

As regards the bell 21 of party line subscriber B, the condenser 20 is normally in a discharged condition since it is connected to the earthed positive line and remains so until the A party's receiver is lifted when a potential with respect to earth of approximately half the exchange battery voltage appears on the line side of condenser 20 due to the current flow from earth at the exchange, positive line, A party's telephone loop, and negative line to battery at the exchange. This potential is of course insufficient to break down the non-linear resistance unit 22 and the charging current through the condenser 20 will therefore be so small that bell 21 will not tinkle. When the A party dials the first digit of the required number, the dial springs in opening remove the potential from the line side of condenser 20 and if any charge has accumulated thereon, it now tends to discharge over the pos-

itive line to earth at the main exchange, but the unit 22 again functions to limit the current flow to a very small value and so prevents tinkling of the bell. When the dial contacts re-make, the potential is reconnected to the line side of condenser 20 whereupon the unit 22 functions as already described.

Similar considerations apply in the case of a call originated by party B, the units 22 and 12 serving to eliminate tinkling of the bells of either of the parties on the line.

It will be appreciated that owing to the normal high resistance of the units 12 and 22 the unbalancing effect of the earth connection made to the party line during dialling and subsequent conversation is negligible.

Considering now incoming calls to the party line subscribers, when it is desired to ring party A an earthed ringing current generator is connected by the final selector of the automatic switch train to the negative leg of the party line, whereupon the full 75 volts ringing voltage is applied across condenser 10, bell 11 and non-linear resistance 12. The unit 12 being normally of very high resistance absorbs practically all the applied voltage, whereupon it breaks down on the first peak and rapidly lowers its resistance. The breakdown condition persists until the applied A. C. voltage reaches a low value, whereupon the unit restores to its normal high resistance and it then subsequently breaks down on the peak of each half cycle of applied A. C. voltage and allows sufficient current to flow to cause satisfactory operation of the bell 21. When it is desired to ring the bell of party line subscriber B, ringing current is applied at the exchange to the positive leg of the line, whereupon unit 22 functions to allow bell 21 to operate satisfactorily in the same manner as unit 12 for party A.

The invention is not limited in scope to the earthed bell party line system described as it may also be applied with advantage to party line systems using different ringing frequencies for the various parties on a party line. In this case differently tuned bells are each connected in series with a condenser across the party line and the insertion of a non-linear resistance device in series with each condenser and bell will serve to avoid tinkling due to dialling or extraneous connections and will also improve the immunity of each circuit to ringing current of frequencies to which it is not tuned.

The invention also has a sphere of usefulness for ordinary substations employing a single telephone instrument per line, particularly where the signalling bell is permanently connected across the line by way of a condenser and a separate condenser is employed for anti-side tone and spark quench purposes. In this case the bell condenser may be replaced by a suitable non-linear resistance device, since this will perform all the direct current isolating functions of the condenser and at the same time prevent any possible bell tinkling due to the causes described.

What I claim as new and desire to secure by Letters Patent is:

1. In a telephone substation, an incoming line upon which a ringing signal of certain voltage is impressed at times and upon which a lower voltage is impressed at other times, a condenser and a ringer connected in series to said line, a calling device operated at said other times, a charging circuit and a discharging circuit for said condenser completed alternately over said ringer by

said calling device, a solid body of non-linear resistance material in series with said ringer presenting a high resistance to the flow of charging and discharging current through said ringer thereby to prevent actuation of said ringer when said calling device is operated, the resistance of said body being effective to decrease responsive to said certain voltage being impressed upon said line, thereby to permit said ringer to respond to said ringing signal.

2. In a telephone system, a party line to which a certain potential is normally connected at the exchange and upon each side of which a ringing signal of a higher potential is sometimes impressed at the exchange, two subscribers' stations on said line, one of said stations having a condenser and a ringer connected in series to one side of said line, the other of said stations having a ringer and condenser connected in series to the other side of said line, a calling device at one of said stations operated at times to transmit impulses over said line to the exchange, a charging circuit and a discharging circuit for the condenser at each station completed alternately over the ringer at the same station whenever the calling device at said one station is operated, a solid body of non-linear resistance material in series with each ringer presenting a high resistance to the flow of charging and discharging current through that ringer, thereby to prevent actuation of both ringers when the calling device at said one station is operated, the resistance of each body being effective to decrease responsive to said certain potential being impressed upon the side of said line to which its associated ringer is connected, thereby to permit said associated ringer to respond to said ringing signal when same is

impressed upon the side of said line to which that ringer is connected.

3. In a telephone substation, an incoming line upon which a ringing signal of certain voltage is impressed at times and upon which a lower voltage is impressed at other times, a transmitter and a receiver, means including a condenser and an induction coil for connecting said transmitter and said receiver to said line in an anti-side tone speech circuit, a solid body of non-linear resistance material, a ringer, a ringing circuit connected to said line and including in series said condenser, said body and said ringer, said body presenting a high resistance to the flow of current through said ringer whenever said lower voltage is applied to said line but reducing its resistance to a low value in the presence of said certain voltage, thereby to permit said ringer to respond to said ringing signal.

4. In a telephone substation, an incoming line upon which a ringing signal of certain voltage is applied at times and upon which a lower voltage is applied at other times, a solid body of non-linear resistance material, and a ringer connected to said line through said resistance material, said material presenting a high resistance to the flow of current through said ringer whenever said lower voltage is applied to said line but reducing its resistance to a low value in the presence of said certain voltage, thereby to permit said ringer to respond to said ringing signal.

5. A substation as claimed in claim 4, wherein said non-linear resistance material comprises a mixture of silicon carbide with carbon and/or tungsten which has been agglomerated under pressure and subsequently baked.
